WILLIAM HENRY HANSELL, OF PHILADELPHIA, PENNSYLVANIA, ASSIGNOR
TO HENRY L. EGBERT, OF NEW YORK, N. Y.

PAPER-CUTTING MACHINE.

SPECIFICATION forming part of Letters Patent No. 744,754, dated November 24, 1903.

Application filed December 8, 1902. Serial No. 134,228. (No model.)

To all whom it may concern:

Be it known that I, WILLIAM HENRY HANSELL, of the city and county of Philadelphia, State of Pennsylvania, have invented an Improvement in Paper-Cutting Machines, of which the following is a specification.

It is one of the objects of my invention to enable the clamp whose operations are controlled by the knife-bar to impose a constant and uniform clamping pressure upon the paper irrespective of the extent of movement of the knife or the depth of the cut.

It is also an object of the invention to produce a uniform clamping pressure upon the paper irrespective of the height of the pile, so that the same clamping pressure will be exerted by the clamp whether the clamp is acting on a single sheet or on a pile of paper several inches in height.

The attainment of these objects insures that the paper may always be clamped with the proper amount of pressure notwithstanding variations in the height of the pile, and consequently defective cutting due to insufficiency of clamping pressure and injury to the paper due to excess of clamping pressure are avoided. It also insures uniform cutting irrespective of the extent of movement of the knife or the height of the pile of paper.

It is also an object of my invention to enable the amount of clamping pressure to be adjusted to suit the character of the paper to be cut, so that injury from excessive clamping pressure in light paper may be avoided.

It is also an object of my invention to insure the application of the full clamping pressure before the knife commences its cutting operation and not to release the clamping pressure until the completion of the cutting operation and the knife has commenced to return.

In carrying out my invention I employ, in combination with the usual reciprocating knife-bar and its knife and the clamping-bar and its clamp, operated by the knife-bar, of pressure-creating devices to impart a constant and uniform pressure to the clamping-bar, which are operated by the knife-bar and controlled by the movements of the clamping-bar in such manner that they are thrown into action when the movement of the clamping-

bar is arrested by the contact of its clamp with the paper, but are uniform in their action and are not affected in the amount of clamping pressure produced by the extent of the movement of the knife-bar.

The particular pressure-creating devices which I prefer to employ in carrying out my invention consist of friction-creating devices, such as a brake-wheel and brake-band, carried by the clamping-bar and operated by the movement of the knife-bar when the movement of the clamping-bar is arrested by the paper. As the amount of clamping pressure depends wholly upon the amount of friction produced by said friction-creating devices, it is obvious that such pressure will be constant and will not be affected by the extent of movement of the knife during the act of cutting or the height of the pile of paper and also that the amount of the clamping pressure may be adjusted to suit the character of the paper to be clamped by the adjustment of the friction-creating devices.

The details of my invention will be better understood by a reference to the accompanying drawings.

Figure 1 is a rear elevation of the upper portion of a paper-cutting machine embodying the invention. Fig. 2 is a front elevation of one end of the clamping-bar. Fig. 3 is a vertical sectional view on the line 3 3 of Fig. 1. Fig. 4 shows a plan and side elevation of the clutch or pawl for operating the friction-wheel. Fig. 5 is a detail plan view of the friction-band. Fig. 6 shows a plan on side elevation of the clutch-operating arm. Fig. 7 shows a plan and side elevation of the pawl-carrying frame. Fig. 8 is a plan view of the friction-wheel, and Fig. 9 is a transverse sectional view of the same on the line 9 9 of Fig. 8.

The clamping-bar *a* is guided in the usual manner in the vertical guides *a' a'* of the main frame and is operated by the knife-bar *b*, by which it is supported by rollers or studs *b'* on the knife-bar, which engage forked levers *c* on the clamping-bar. Only one pair of these forked levers and rollers is shown in Fig. 2; but it is to be understood that two are used in practice, one set located at each end.

The knife-bar *b* is operated in the usual

manner to reciprocate vertically and to have a longitudinal movement. As the means for imparting these movements to the knife-bar are usual and well known in the art and form 5 no part of my invention, they are not shown in detail, though one of the knife-bar-operating arms or links b^2 is shown at one end of the machine in Fig. 1.

The forked levers c are provided with 10 toothed segments d , which engage a pinion e , carried on a pin e' , journaled in the clamping-bar. Secured to the outer end of the pin e' is a cross-bar f , provided on its ends with lugs g .

15 The pin e' is journaled in a hub j' of the clamping-bar, and journaled loosely on the hub j' is a band or brake wheel j , which is embraced by a brake-band k .

A ring frame h , supported on the hub m of 20 the band or brake wheel, carries two pivoted pawls or dogs i , which are pivoted at i' in recesses i^2 in the ring frame and are adapted when rocked to move inwardly into contact with the surface of the hub m of the brake- 25 wheel.

The pawls or clutches i are provided with arms n , having more or less elongated slots n' , which are engaged by the lugs g of the cross-bar f .

30 The brake-band k encircles the brake-wheel with frictional contact, the amount of which may be adjusted to produce the desired pressure in the clamping-bar. In the construction shown the brake-band consists of two 35 members k' k^2 , hinged together at k^3 . One end of the brake-band is fastened to the frame of the clamping-bar, as at k^4 , and the other end is connected with adjustable devices to regulate the tension, which, as shown, consist of a longitudinally-adjustable rod o . The rod is shown provided on its end with a strap o' , encircling an eccentric p on a crank-arm p' , journaled in the clamping-bar and provided with a pin p^2 , which is engaged by 45 a jaw t of a link t' , hinged at t^2 to a crank-arm t^3 of a pin t^5 , journaled in the clamping-bar frame and carrying a wheel t^4 , by which the arm t^3 may be adjusted to adjust the rod and the tension of the brake-bands k .

50 In the machine shown in the drawings there are two of these pressure-creating devices, and the brake-band of each is connected with the rod o , so that both bands may be adjusted simultaneously and equally. The rod o is 55 also made with adjustable sections o^2 , so that one brake-band may be adjusted independently of the other to compensate for any inequality in wear between the two band-wheels or other parts of the two pressure-creating devices.

In smaller machines only one of the pressure-creating devices is required.

When the clamping-bar and knife-bar are in elevated position, the clamping-bar is supported wholly by the knife-bar by the rollers b' and pivoted forks c which are held against upward movement by the lugs c' , Fig. 2. As

the knife-bar descends it lowers the clamping-bar with it without movement in the pivoted forks c until the clamp is in contact 70 with the surface of the paper. When the movement of the clamping-bar is arrested by the paper, the knife s is elevated a short distance (in practice about an inch) above the clamping-surface, and as the knife-bar continues to descend the forks c are rocked by the pins b' and the pinions e are rotated by the segments d . The rotation of the pinions e turns the cross-bars f through the pins e' , and the lugs g of the cross-bars move inward 80 in the slots n' of the pawls, and thus throw the pawls into engagement with the surface of the hubs m of the band-wheels. This causes the band-wheels to rotate with the pinions e' in frictional contact with the brake-bands k , and as the clamping-bar is resting on the paper the movement of the knife-bar will impart to the clamp a pressure proportional to the friction of the brake-bands on the band-wheels. 85

90 As the pressure is produced by the friction of the brake-bands on the band-wheels it is constant and uniform and does not increase as the knife continues to descend, so that throughout the cutting action the same pressure is maintained.

95 As the pressure is produced when the clamping-bar is brought in contact with the paper and wholly by the action of the brake-bands, it is obvious that the pressure will be the same irrespective of the height of the paper or the depth of the cut. In practice it has been demonstrated that exactly the same pressure is produced on a single sheet as on the surface of a pile several inches high. 100

105 By so locating the knife that it is elevated slightly above the clamp, as shown in Fig. 3, the clamping pressure will be applied before the knife comes into cutting action. While the slight lost motion due to the movement 110 of the lugs g in the elongated slots n' of the pawls or clutches i permits a slight movement of the knife after the clamp makes contact with the paper and before the clamping pressure is applied by the operation of the 115 friction-creating devices, the extent of this lost motion is not sufficient to enable the knife to come into cutting action before the clamping pressure is applied; but on the return movement this lost motion is of special 120 advantage, since it enables the knife to rise slightly before the pressure-creating devices are released, and thus insures the maintenance of the clamping pressure until after the cut is finished. 125

On the return movement the segments d and pinions e are rocked back. This moves the lugs g outward in the slots n' and disengages the clutches i from the hubs m of the band-wheels, thus throwing the friction- 130 creating devices out of action.

The details of the construction shown may be varied without departing from the spirit of my invention.

What I claim as new, and desire to secure by Letters Patent, is as follows:

1. In a paper-cutting machine, the combination with a reciprocating knife-bar and knife, of a reciprocating clamping-bar and clamp, and means carried by the knife-bar to operate the clamping-bar embracing pressure-creating devices actuated by the stoppage of the clamping-bar to impart a uniform pressure thereto irrespective of the extent of movement of the knife-bar.

2. In a paper-cutting machine, the combination with a reciprocating knife-bar and knife, of a reciprocating clamping-bar and clamp and means carried by the knife-bar to operate the clamping-bar embracing pressure-creating devices to impart pressure to the clamping-bar when the clamp is in contact with the paper.

3. In a paper-cutting machine, the combination with a reciprocating knife-bar and knife, of a reciprocating clamping-bar and clamp, means carried by the knife-bar to operate the clamping-bar embracing pressure-creating devices adapted to impart a uniform pressure to the clamping-bar when the movement of the clamping-bar is arrested irrespective of the extent of movement of the knife-bar, and means to regulate said pressure-creating devices to vary the amount of pressure produced thereby.

4. In a paper-cutting machine, the combination with a reciprocating knife-bar and knife, of a reciprocating clamping-bar and clamp operated by the knife-bar, and friction-creating devices carried by the clamping-bar and operated by the movement of the knife-bar under the control of the reciprocation of the clamping-bar, whereby said friction-creating devices are thrown into operation by the movement of the knife-bar, when the movement of the clamping-bar is arrested by the paper, and a uniform pressure is imparted to the clamping-bar irrespective of the extent of movement of the knife-bar or the height of the paper being cut.

5. In a paper-cutting machine, the combination with the reciprocating knife-bar and knife, of a reciprocating clamping-bar and clamp operated by the knife-bar, friction-creating devices carried by the clamping-bar, means operated by the movement of the knife-bar and controlled by the movement of the clamping-bar to operate said friction-creating devices when the movement of the clamping-bar is arrested, embracing clutch devices adapted to act upon the friction-creating devices.

6. In a paper-cutting machine, the combination with the reciprocating knife-bar and knife, of a reciprocating clamping-bar and clamp operated by the knife-bar, friction-creating devices carried by the clamping-bar, means operated by the movement of the knife-bar and controlled by the movement of the clamping-bar to operate said friction-creating devices when the movement of the clamp-

ing-bar is arrested, embracing clutch devices adapted to act upon the friction-creating devices, said clutch devices having provision for lost motion whereby a slight movement may be permitted in the knife-bar after the clamping-bar is arrested before said clutch devices operate the friction-creating devices.

7. In a paper-cutting machine, the combination with the reciprocating knife-bar and knife, of a reciprocating clamping-bar and clamp operated by the knife-bar, a brake-wheel carried by the clamping-bar, a brake acting on said band-wheel to impose a uniform friction thereon when the brake-wheel is operated, and means operated by the movement of the knife-bar and controlled by the movement of the clamping-bar to rotate said brake-wheel when the movement of the clamping-bar is arrested by the paper to be cut.

8. In a paper-cutting machine, the combination with the reciprocating knife-bar and knife, of a reciprocating clamping-bar and clamp operated by the knife-bar, a brake-wheel carried by the clamping-bar, a brake acting on said brake-wheel to impose a uniform friction thereon when the brake-wheel is operated, clutch devices adapted to act on the brake-wheel, operated by the movement of the knife-bar and controlled by the movement of the clamping-bar, to rotate the brake-wheel when the movement of the clamping-bar is arrested by the paper to be cut.

9. In a paper-cutting machine, the combination with the reciprocating knife-bar and knife, of a reciprocating clamping-bar and clamp operated by the knife-bar, a brake-wheel carried by the clamping-bar, a brake carried by the clamping-bar and adapted to act on said brake-wheel, a clutch device adapted to act on the brake-wheel, means to actuate said clutch device, a pinion on the clamping-bar for operating said means to actuate the clutch device, and means operated by the movement of the knife-bar and controlled by the movement of the clamping-bar to actuate said pinion, when the movement of the clamping-bar is arrested.

10. In a paper-cutting machine, the combination with the reciprocating knife-bar and knife, of a reciprocating clamping-bar and clamp operated by the knife-bar, a brake-wheel carried by the clamping-bar, a brake carried by the clamping-bar and adapted to act on said brake-wheel, a pivoted segment carried by the clamping-bar and adapted to be operated by the knife-bar when the movement of the clamping-bar is arrested, a pinion engaging said segment, a clutch-frame arranged adjacent to said brake-wheel, movable clutches carried by said clutch-frame and adapted to engage the brake-wheel, and means operated by the pinion to control said clutches and throw them into engagement with the brake-wheel when said pinion is operated in one direction and to release them when the pinion is operated in the other direction.

11. In a paper-cutting machine, the combi-

nation with the reciprocating knife-bar and knife, of a reciprocating clamping - bar and clamp operated by the knife - bar, a brake-wheel carried by the clamping-bar, a brake 5 carried by the clamping - bar and adapted to act on said brake - wheel, a pivoted segment carried by the clamping-bar and adapted to be operated by the knife-bar when the movement of the clamping-bar is arrested, a 10 pinion engaging said segment, a clutch-frame arranged adjacent to said brake-wheel, movable clutches *i* carried by said clutch-frame

and provided with slotted arms *n*, and adapted when operated to engage the brake-wheel, a cross-bar *f* operated by the pinion and provided with lugs *g* engaging the slotted arms *n* of the clutches, substantially as and for the purposes described. 15

In testimony of which invention I have hereunto set my hand.
